US0D1013660S

(12) **United States Design Patent** (10) Patent No.: **US D1,013,660 S**
Kuramoto (45) Date of Patent: ** Feb. 6, 2024

(54) **CONTROLLER FOR DIGITAL AUDIO
PLAYER**

(71) Applicant: **AlphaTheta Corporation**, Yokohama (JP)

(72) Inventor: **Takahiro Kuramoto**, Yokohama (JP)

(73) Assignee: **ALPHATHETA CORPORATION**, Yokohama (JP)

(**) Term: **15 Years**

(21) Appl. No.: **29/782,620**

(22) Filed: **May 7, 2021**

(30) **Foreign Application Priority Data**

Nov. 11, 2020 (JP) ..... 2020-024281 D

(51) **LOC (14) Cl.** **14-01**

(52) **U.S. Cl.**

USPC **D14/217**
